HAIR WAVER

Maggie T. Viggers, Lafayette, Colo.

Application May 7, 1937, Serial No. 141,215

7 Claims. (Cl. 132—38)

This invention relates to improvements in hair wavers of the type employed for giving hair a wavy appearance.

This invention has reference more particularly to that general type of hair wavers in which each unit consists of two arcuate combs hingedly connected by means of two links of equal length so as to form a deformable parallelogram in which the two combs can move relative to each other in opposite directions and in arcuate paths.

It is the object of this invention to produce a hair waver that can be employed by any woman for waving her own hair or the hair of others, and which shall be of simple and substantial construction.

Another object is to produce a hair waver in which the combs shall be so designed that the two combs may be duplicates and therefore require only a single die for their construction and in which the ends of the combs shall have integral projections that can be rolled to form tubular bearings for the connecting links and which therefore simplify and cheapen the construction.

Another object is to produce a device of the class described in which the links may be formed from single pieces of wire, bent into a widened U-shape, in which the parallel sides extend through the tubular bearings to form the pivotal connections and in this way to simplify and cheapen the construction and the assembly.

A still further object is to produce a hair waving device of the type indicated in which the adjacent surfaces of the combs have integral stops that limit the movement of the combs towards each other and which assure that the hair will not be pinched between the combs.

Another object is to produce a hair waver of the type indicated in which each comb shall be provided with a latch member that engages the other comb and which assures that the combs will be held in uniformly spaced relation.

Another object is to produce a hair waver of the type indicated in which the teeth of the two combs are slanted in opposite directions for the purpose of preventing the hair from slipping off during use.

A further object is to produce a hair waver of the type having two combs, curved longitudinally, with teeth on their concave edges and so interconnected that the concave edges will always remain in parallel position regardless of the longitudinal position of the combs.

The above and other objects that may appear as the description proceeds are attained by means of a construction and arrangement of parts that

will now be described in detail, reference for this purpose being had to the accompanying drawing in which the invention has been shown in its preferred form and in which:

Figure 1 is a side elevation of one of the waver units, showing the combs in maximum longitudinally offset position;

Figure 2 is a top plan view of the unit shown in Fig. 1;

Figure 3 is a section taken on the line 3—3 Fig. 10 2;

Figure 4 is a top plan view similar to that shown in Fig. 2, but with the combs in maximum spaced position;

Figure 5 is a section, similar to that shown in Fig. 3, taken on line 5—5 Fig. 8;

Figure 6 is a fragmentary side elevation similar to that shown in Fig. 1 and shows a modification in which the teeth are inclined in opposite directions relative to a radius of curvature;

Figure 7 is a diagrammatic view showing the combs in maximum spaced position and showing a hair in position;

Figure 8 shows the combs displaced longitudinally and indicates the position taken by a hair;

Figure 9 indicates, in a diagrammatic manner, how several waver units can be assembled end to end to form an elongated arc;

Figure 10 is a side view of the units shown in Fig. 9 and shows how the several units form an arc of extended length; and

Figure 11 shows one end of a comb blank, and shows the integral projection that is bent into a tubular bearing for one end of a link.

In the drawing, reference numeral 12 designates the combs, which, as above stated, are duplicates. The combs are curved in the direction of their length and the concave edges are provided with teeth 13, which in the embodiment illustrated in Fig. 1 are radial or parallel with a radius of curvature. In Fig. 6, the teeth have been shown as inclined with respect to a radius of curvature. The convex edges of the combs are strengthened, either by a roll 14 as shown in Figs. 1, 2, 3, 4, and 6, or by a semi-circular flange 15 like that shown in Fig. 5.

Referring now more particularly to Fig. 11, it will be seen that the blanks from which the combs are made have teeth formed along their concave edges and are provided at their ends with projecting lugs or ears 16 that may be rolled to form tubular bearings 16a whose axes are parallel to a radius of curvature, or in other words, the axes of the tubular bearings, when extended, intersect at the center of curvature 55.

of the combs. The center of curvature has not been shown for lack of room, but the dotted lines 17 designate radii of curvature and if prolonged intersect at the center of curvature.

- 5 The combs are connected at their ends by means of links 18 whose ends 19 are substantially parallel and the shape of these links has therefore been described as a "widened U". After the links are in position, the ends of the sides 19 are bent 10 slightly, as indicated by numeral 20, to prevent them from being accidentally withdrawn from the bearings.

The convex edges of the combs are preferably rolled as indicated in the drawing by reference 15 number 14, but since this requires an additional operation, the convex edges, instead of forming a complete roll, may be bent into a semi-circular flange 15 as indicated in Fig. 5.

- 20 The combs may be bent so that one flat side is concave and the other convex, and this has been indicated in Fig. 2. This additional curvature, 25 however, introduces certain complications in the manufacture, especially if inclined teeth like those shown in Fig. 6 are employed and the combs are therefore preferably made straight.

The length of the combs, as well as their width, may be varied to suit the convenience of manufacture and marketing.

- 30 It will be noticed that each comb has one or more, preferably two, projections or bosses 21 that serve as stops and limit the movement of the combs towards each other, in the manner shown in Fig. 2. The object of the stops 21 is to prevent the combs from compressing the hair as 35 this would injure the appearance of the waves.

Each comb is provided with a latch that is adapted to engage with the other comb of each assembly. The latches have each an arm 22 that is connected with the comb, for pivotal movement, by means of a rivet 23; the other end is bent 40 into the form of a hook 24 that is shaped to lap the convex edge of the other comb in the manner shown most clearly in Fig. 3. The latches may be provided with projecting portions 25 to 45 facilitate opening and closing the latch.

When the waving device is to be applied to the hair, the combs are spread apart in the manner shown in Figs. 4 and 7, and the device is then applied to a strand of hair in the manner shown 50 in Fig. 7 where the single line 26 designates a strand of hair. The combs are now moved longitudinally relative to each other, as indicated in Fig. 8, until they come to the position shown in Figs. 2 and 5 in which position they are then 55 latched.

Figs. 7, 8, and 9 show the position taken by the hair. The loop indicated by 27 in Fig. 5 may be much lower than shown there and may be absent entirely.

60 In some cases, it is desirable to have the teeth of the combs oppositely inclined with respect to a radial line, as shown in Fig. 6, as such a construction serves to hold the hair from slipping off.

65 In Fig. 9, three units have been shown, arranged end to end. Owing to the displacement of the ends of the combs relative to each other, the ends of the several units overlap when arranged as shown in Figs. 9 and 10.

70 These wavers can be employed for retracing permanents or finger waves or may be used for making new waves.

75 Owing to the design of the combs, they may be duplicates which necessitates only a single die for both combs. The links may also be made by

means of dies and the construction can therefore be reduced in cost to a very low figure.

The material is preferably metal, such as aluminum, but other materials such as hard rubber, celluloid or other similar materials may be 5 used.

From the above, it will be apparent that the present invention makes it possible to produce a hair waver with a very small number of special tools because, aside from the latch, two dies only 10 are required, one for the combs and one for the links and as these are simple, their cost is small.

Having described the invention what is claimed as new is:

1. A comb for use in a hair waving device 15 having two substantially identical combs hinged-ly connected at their ends by links of equal length, said comb having its ends formed with tubular projections forming hinge bearings.

2. In a hair waving device, two combs, curved 20 in the direction of their length, into arcuate form, the ends of each comb having an integral portion thereof formed into a hinge bearing, the axes of the two bearings intersecting at the center of curvature of the combs, and links of equal 25 length and of widened U-shape connecting corresponding end bearings, the parallel side members of the links being journalled in the bearings.

3. In a hair waving device, two combs, curved 30 in the direction of their length, the teeth being 35 on the concave edge, the ends of the combs having integral tubular extensions forming bearings, the axes of the bearings intersecting at the center of curvature, the convex edges of the combs being flanged to stiffen them, corresponding ends 40 of the combs being connected by means of links of widened U-shape, the links at opposite ends being of the same length, the parallel sides of the links being journalled in the bearings whereby the combs and the links form a deformable parallelogram in which the combs have an arcuate movement relative to each other.

4. In a hair waving device, two combs, curved 45 in the direction of their length, the teeth being on the concave edge, the ends of the combs having integral tubular extensions forming bearings, the axes of the bearings intersecting at the center of curvature, the convex edges of the combs being flanged to stiffen them, corresponding ends 50 of the combs being connected by means of links of widened U-shape, the links at opposite ends being of the same length, the parallel sides of the links being journalled in the bearings whereby the combs and the links form a deformable parallelogram in which the combs have an arcuate 55 movement relative to each other, and projections on adjacent surfaces of the combs for limiting their movement towards each other.

5. In a hair waving device, two combs, curved 60 in the direction of their length, the teeth being on the concave edge, the ends of the combs having integral tubular extensions forming bearings, the axes of the bearings intersecting at the center of curvature, the convex edges of the combs being flanged to stiffen them, corresponding ends 65 of the combs being connected by means of links of widened U-shape, the links at opposite ends being of the same length, the parallel sides of the links being journalled in the bearings whereby the combs and the links form a deformable parallelogram in which the combs have an arcuate 70 movement relative to each other, projections on adjacent surfaces of the combs for limiting their movement towards each other, and means for latching the combs in stop engaging position. 75

6. A blank for a comb to be employed in a hair waving device of the class described, comprising an arcuate piece of metal having comb teeth on its concave edge, the ends of the blank having projecting ears adapted to be rolled to form bearings whose axes intersect at the center of curvature, that portion of the blank that projects beyond the arc defining the outer edges of the ears, being adapted to be bent along the line of the arc into a reenforcing means for resisting transverse flexure.

7. A comb for use in a hair waver of the type in which two combs are connected by parallel links of equal length so as to form a changeable rectangle, comprising an arcuate sheet of material having its concave edge provided with teeth, its convex edge provided with a reenforcing flange and its ends provided with tubular bearings whose axes intersect at the center of curvature.
